DESIGN FOR A DOUBLE-HEADED DOLL

Florence B. Salter, New Orleans, La., assignor of twenty-four per cent to Gilbert D. Gayaut and twenty-eight per cent to Kathryn Rhodes, New Orleans, La.

Application October 3, 1945, Serial No. 122,473

Term of patent 7 years

(Cl. D34—4)

To all whom it may concern:

Be it known that I, Florence B. Salter, a citizen of the United States, residing at New Orleans, in the Parish of Orleans and State of Louisiana, have invented a new, original, and ornamental Design for a Double-Headed Doll, of which the following is a specification, reference being had to the accompanying drawing, forming part thereof.

I claim:

The ornamental design for a double-headed doll, as shown and described.

FLORENCE B. SALTER.
